SANITARY NAPKIN

Robert W. Johnson, New Brunswick, N. J., assignor to Johnson & Johnson, New Brunswick, N. J., a corporation of New Jersey

Application July 19, 1930. Serial No. 469,165

2 Claims. (Cl. 128—290)

This invention was devised to correct or obviate certain objectionable features of sanitary napkins of the single use or easily disposable type and otherwise to improve the same.

5 As ordinarily constructed such articles include a core or filling of cellulosic or other absorbent and disintegratable material in the form of a pad of superimposed sheets the edges of which are rough-cut or jagged and consequently tend to irritation and other sources of discomfort not 10 obviated and not alleviated by the usual gauze wrapping which of itself is hard and abrasive to the touch.

Hence, the problem is to correct the condition 15 stated and to insure greater efficiency and a greater degree of comfort without appreciably adding to the cost of the article.

The nature, characteristic features and scope 20 of the invention more readily will be understood from the following detailed description taken in connection with the accompanying drawings, forming a part hereof, wherein

Figure 1 is a perspective view, partly in longitudinal section, of a sanitary napkin embodying 25 my improvements.

Fig. 2 is a transverse section of the pad and facing elements in flat state, the gauze wrapper being omitted.

Fig. 3 is a transverse section of the complete 30 article bent to U-form, showing how the facing elements overlie the rough marginal edges or walls of the pad.

Fig. 4 is a plan view of one of the facing elements.

35 Figs. 5 and 6 are details showing varied forms of facing elements.

In the drawings, 5 represents a standard or other suitable core or filling formed or constructed of readily disposable material, and 40 6 represents the usual gauze wrapper folded longitudinally to enclose the pad and to provide the usual tabs 7.

According to my invention there is provided 45 above and below the pad and between the same and the gauze, facing elements, as at 8 and 9, consisting of a layer or bat of soft, conformable, absorbent material such as by preference absorbent cotton. It will be understood that the facing elements 8 and 9 are disposed for independence 50 with respect to the pad in order to promote the maximum degree of softness and conformability and so as completely to invest or cover the rough, irregular, ragged and crudely assembled or non-registering edges, which in the absence of cushioning elements would make for irritation and

other sources of extreme discomfort. In the further advancement of my inventive thought, the soft pads or facing elements are provided with marginal extensions or wings 10 which may be of the square outline, Fig. 4, or which may be 60 of the general arch form as indicated at 11 in Fig. 6.

The merit and significance of the soft pads or facings is graphically shown in the bent U-form, Fig. 3, wherein those elements not only 65 are disclosed as covering the larger areas of the filling thereby softening the gauze wrapper to an appreciable extent, but are shown as providing, through their overlap, a double cushion for the rough marginal walls of the filling. The 70 construction has the further merit that it makes the article usable as to either side thereof. In short, there are no right and wrong sides requiring the presence of some indicia properly to distinguish them.

75 What is claimed as new is:

1. A liner for sanitary napkins of the disposable type, comprising a bat of soft fibrous absorbent material of substantially rectangular form having arcuate terminals inwardly of the side margins, whereby the side margins are defined as offsettable wings, substantially as and for the purpose described.

2. A sanitary napkin of the throw-away type, comprising a core or filling of the rounded end 85 type, bats of soft fibrous absorbent material of substantially rectangular form with arcuate terminals inwardly of the side margins thereof, whereby the side margins are defined as offsettable wings which overlie the edges of the 90 filling and reduce the abrasive character thereof, and a gauze casing surrounding said parts.

ROBERT W. JOHNSON.
